UNITED STATES PATENT OFFICE.

ERNEST G. H. SCHENCK, OF ORANGE, NEW JERSEY.

DESIGN FOR A CUT STONE.

SPECIFICATION forming part of Design No. 36,167, dated December 16, 1902.

Application filed November 15, 1902. Serial No. 131,493. Term of patent 7 years.

To all whom it may concern:

Be it known that I, ERNEST G. H. SCHENCK, a subject of the King of Belgium, and a resident of Orange, New Jersey, have invented a certain new, original, and ornamental Design for a Cut Stone, of which the following is a clear, full, and exact description.

In the drawings, Figure 1 is a plan view of the bottom of the stone cut in accordance with my design; and Fig. 2 is a view showing the same stone in side elevation, a top for the stone being indicated in dotted lines.

In the embodiment of my design shown in the drawings it consists of a figure having a generally circular outline in plan view and in side elevation of a generally conical shape from the edges of the circular outline toward the center of the design. Within the circular outline is a star-shaped figure made up of a

plurality of pointed figures *a*, meeting in the center at a point. Between these figures are a plurality of elongated pointed figures *b b*, extending to the circumference of the design, and between these figures *b b* are figures *c*, extending from the figures *a* to the circumference of the design and bounded by side lines, which diverge outwardly to the circumference of the design.

What I claim is—

The ornamental design for a cut stone, substantially as shown and described.

Signed at New York, N. Y., this 5th day of November, 1902.

ERNEST G. H. SCHENCK.
